SINK MOUNTING

Herbert D. Drain, Chicago, Ill., assignor to Walter E. Selck and Co., Chicago, Ill., a corporation of Illinois

Application December 29, 1950, Serial No. 203,319

6 Claims. (Cl. 4—187)

1

This invention relates to improvements in sink mountings for installing a standard flat flange type sink in an opening in a drainboard, cabinet top or similar supporting structure.

It is a general object of the invention to provide an improved mounting means adapted for rigidly securing a flat flange type sink in an opening in a drainboard or cabinet top which mounting means comprises a sealing ring or molding strip of generally T-shaped cross section which is adapted to be positioned between the edge of the sink flange and the edge of the drainboard in overlapped relation with respect to the sink flange and the top of the drainboard and a plurality of adjustable clamping members which are adapted to be positioned beneath the sink and the drainboard to rigidly secure the sealing ring in such relation and to provide a watertight seal between the sink and the drainboard.

It is a more specific object of the invention to provide a sink mounting means of the type described wherein a plurality of clamping members are provided for initially clamping the T-shaped sealing member in overlapped relation with respect to the sink frame, prior to installation of the same as a unit in the aperture in the drainboard.

It is a still more specific object of the invention to provide a sink mounting means for combination with a flat rim type sink which comprises a molding frame of generally T-shaped cross section having a top portion adapted to overlie the sink rim and the edge of the apertured drainboard or cabinet top structure in which the sink is positioned and a plurality of clamping elements for initially securing the molding frame to the sink rim whereby the sink and the molding frame may be installed as a unit in the drainboard or top, the clamping elements each comprising an elongate plate-like portion having an adjusting screw in threaded engagement in an aperture adjacent one end thereof and having a groove extending along the other end thereof which is adapted to receive in interlocking relation a shoulder formation along the lower edge of the molding frame.

These and other objects of the invention will be apparent from a consideration of the preferred form thereof which is shown by way of illustration, in the accompanying drawings, wherein:

Fig. 1 is a top plan of a sink installed in a drainboard with a mounting means which embodies the principles of the invention;

Fig. 2 is a bottom view of the sink installation shown in Fig. 1;

2

Fig. 3 is a section on the line 3—3 of Fig. 1, to an enlarged scale;

Fig. 4 is a perspective view showing, in inverted position, a portion of a molding frame and one of the clamping elements initially securing the same to the rim of the sink;

Fig. 5 is a section on the line 5—5 of Fig. 1, to an enlarged scale; and

Fig. 6 is a perspective view showing a portion of the molding frame secured to the sink rim and the drainboard by one of the clamping elements.

Referring to the drawings there is illustrated a sink 10 having a flange portion 11 which is positioned in an aperture 12 provided in a drainboard structure 13 and which is secured therein by a sealing ring or molding 14 and a plurality of clamping elements 15. The sink 10 is the standard type having an outwardly directed top rim or flange structure 11 which is rounded at the corners of the sink. The drainboard 13 is a conventional linoleum covered plywood structure which may be a cabinet top or other supporting surface.

The sealing ring or molding 14 is a one-piece member, preferably of extruded metal, which is adapted to be positioned around the periphery of the sink flange 11 with one side or top portion 16 extending in overlying relation to the top surface of the sink flange 11 and with the other side or top portion 17 extending in overlying relation to the adjoining top surface of the drainboard 13. The sealing ring 14 includes a depending web or stem portion 18 which is adapted to be positioned in the space between the outer edge of the sink flange 11 and the edge of the drainboard 13 which surrounds the aperture 12. The sealing ring web or flange 18 is provided along its lower inner edge with a thickened portion or shoulder formation 19 extending inwardly thereof and providing bottom 20 and an inwardly facing side edge 21. The top edge 22 on the shoulder formation 19 extends at a slight downward angle towards the main portion of the web 18 so that there is provided a hook-like formation along the bottom edge of the same. The depth of the web 18 is sufficient to bring the bottom edge 20 approximately on the level with the bottom edge of the drainboard 13 in which the sink is mounted and below the bottom surface of the rim 11 of the sink 10.

In installing a sink of this character in a drainboard it is convenient, particularly in the case of cabinet tops, to first attach the molding or sealing strip 14 to the flange 11 of the sink 10 and then insert or position the sink and molding as a unit in the aperture 12.

A plurality of attaching or clamping members 23 are provided for initially attaching the molding 14 to the sink flange 11. Referring particularly to Figs. 3 and 4, the molding attaching elements 23 each comprise a generally rectangular body portion 24 having a threaded aperture 25 in one end thereof which is adapted to receive a clamping screw 26. At the other end the element 23 is thickened to provide an upwardly extending off-set portion in which there is formed a groove 27 defined by bottom surface 28, side or vertical surface 29 and top surface 30, the latter being inclined slightly toward the bottom surface 28. The attaching elements 23 are initially positioned on the sealing ring 14 with the shoulder 19 engaged in the grooves 27 and arranged at the four corners of the sink 10, as indicated in Fig. 1. The screws 26 are then drawn up to engage with the bottom of the sink flange 11 to secure the sealing ring 14 firmly in position on the sink 10. The attaching members 23 extend inwardly of the sealing ring 14 and are locked against downward rotative movement relative to the sealing ring 14, so that the screws 26 operate to clamp the sealing ring 14 to the sink rim 11, by engagement of the surfaces 28 and 30 of the members 23 with the surfaces 20 and 22 at the bottom of the web 18 of the sealing ring 14.

The clamping elements 15 which secure the molding 14, the sink 10, and the drainboard 13 in assembled relation, each comprise a generally rectangular plate or body portion 31. The one end of the plate 31 is provided with a threaded aperture 32 and a clamping screw 33 is secured in adjustable relation therein. Intermediate the ends of the plate 31 there is provided an upstanding hook-like formation 34, the undersurface 35 of the hook end of which is beveled or downwardly sloping for cooperation with the top surface 22 of the shoulder 19 on the bottom of the web 18 of the molding 14. A plurality of the elements 15 are arranged in spaced relation around the web 18 of the molding 14 with the opposite ends of the plate portion 31 extending beneath the drainboard 13 and flange 11 of the sink 10 as illustrated in Figs. 5 and 6. The hook or groove formations 34 on the elements 15 are so constructed that the elements pivot about the shoulder or rib 19 on the bottom of the web 18 when engaged therewith. The clamping elements 15 are positioned with the apertured end extending beneath the flange 11 of the sink 10 and with the opposite end beneath the drainboard. Thereafter the adjusting screws 33 are taken up to clamp the elements in position. The screws 33 tend to force the flange 11 into snug relation with the inner top portion 16 of the sealing ring 14 and also to force the opposite ends of the elements 15 into clamping relation with the bottom of the drainboard 13 and the outer top portion 17 of the molding 14 into tight engagement with the top of the drainboard 13.

The molding frame 14 and the attaching and clamping members 23 and 15 are provided as a kit for use when the sink 10 is installed in the aperture 12 of the drainboard 13. The molding or sealing ring 14 is first secured to the flange 11 of the sink 10 by means of the attaching elements 23. This may be conveniently accomplished by positioning the molding 14 with the flange in upstanding relation and setting the sink 10 within the molding 14 in inverted relation with the flange 11 engaging the inner top portion 16 of the molding 14. The elements 23, preferably at least four in number, are engaged with the

shoulder 19 on the bottom edge of the web 18 and the screws 26 are then adjusted to clamp the molding 14 into tight engagement on the sink flange 11. Thereafter the sink is positioned in the opening 12 either in upright or inverted relation. In this position the other top portion 17 of the molding 14 is in engagement with the top surface of the drainboard 13. Thereafter the clamping elements 15 are positioned on the shoulder 19 of the web 18 and the screws 33 are adjusted to clamp the members into tight engagement.

While specific details of construction have been referred to in describing the illustrated form of the invention it will be understood that other details may be resorted to within the spirit of the same.

I claim:

1. In combination with a flat rim type sink adapted to be mounted within an opening in a supporting structure, a molding frame of generally T-shape cross section having a top portion adapted to overlie the sink rim and the marginal edge of said structure around said opening and a vertical portion extending therebetween, said vertical portion having a hook-like shoulder adjacent the lower edge thereof, a plurality of elements for attaching the frame to the sink, said attaching elements each having interlocking engagement with said shoulder and having an adjustable member engaging said sink rim, and a plurality of clamping elements each having intermediate the ends thereof a hook-like formation for pivotal engagement with the shoulder on said vertical portion of said molding frame, said clamping elements having the opposite ends thereof extending beneath the sink rim and the supporting structure, and said clamping elements having an adjustable means for clamping engagement with said sink rim.

2. Mounting means for supporting a flat rim type sink within an opening in a supporting structure, said mounting means comprising a molding frame of generally T-shape cross section having a top portion adapted to overlie the sink rim and the adjoining supporting structure and a vertical portion having a ledge forming rib member adjacent the lower edge thereof, a plurality of elements for initially attaching the frame to the sink, said attaching elements each having a grooved end for interlocking engagement with said rib member and having an adjustable member for engaging beneath said sink rim and a plurality of securing elements having intermediate the ends thereof a transverse groove formation for engagement with the rib member on said vertical portion of said molding frame with the opposite ends thereof extending beneath the sink rim and the supporting structure, said securing elements having an adjustable means for clamping engagement with the bottom of said sink rim.

3. Means for holding a sink having a generally flat peripheral rim within a frame to permit downward insertion of the sink and frame as a unit into an opening in a generally flat horizontal supporting structure, comprising the combination with a mounting frame of generally T-shaped cross section having a top portion which is adapted to overlie both the rim of the sink and the edge of the opening and a vertical web portion which is adapted to extend downwardly between said rim and edge, of a plurality of holding devices for coaction with the rim of the sink

and the web portion of the frame, each of said holding devices consisting of a rigid element which is spaced in its entirety substantially below the top portion of the frame for a distance greater than the thickness of the rim of the sink for coaction only with the lower part of the web portion and which is adapted to project inwardly from said web portion below said rim, and complementary locking formations provided respectively on the web portion adjacent the lower edge thereof and on each element adjacent the outer end thereof, which formations interlock with each other against tilting movement in one direction to secure the element to the lower part of the web portion and prevent the inner end of the element from moving downwardly, and a screw mounted in and projecting upwardly from the inner end of each element for adjustably clamped engagement with the rim of the sink.

4. Means for initially holding a peripherally rimmed sink within a surrounding frame to permit downward insertion of the sink and frame as a unit in an opening in a generally flat supporting structure, comprising the combination with a mounting frame of generally T-shaped cross section having a top portion which is adapted to overlie both the rim of the sink and the edge of the opening in the supporting structure and a vertical web portion which is adapted to extend downwardly between said rim and edge, which web portion is provided adjacent its lower edge with an inwardly and upwardly directed hook formation and with a downwardly facing abutment surface spaced below said hook formation, a plurality of holding devices for coaction with the rim of the sink and the web portion of the frame, each of said holding devices consisting of an element which is adapted to extend inwardly from said web portion and which is provided adjacent its outer end with an outwardly and downwardly directed hook formation and with an upwardly facing abutment surface spaced below said hook formation, which hook formation and abutment surface are adapted respectively to interfit and positively lock with the hook formation and abutment surface on the web portion of the frame to hold the inner end of the element against downward movement, and a screw carried by the inner end of the element for adjustably clamped engagement with the underside of the rim of the sink.

5. A mounting for positioning a flange type sink in an apertured supporting structure comprising a mounting frame having a top portion adapted to extend laterally over the top surface of the sink rim and the adjacent edge of the supporting structure and a stem portion adapted to depend between the sink rim and the edge of the supporting structure, said stem portion having an upwardly directed hook-like shoulder formation

55
60

adjacent the bottom edge thereof projecting inwardly of the stem portion toward the sink, and a plurality of fastening elements for securing the frame to the sink rim, each of said fastening elements having a screw mounting portion at one end adapted to be positioned in inwardly extending relation beneath the sink rim and an abutment forming portion at the other end adapted to be engaged with the bottom edge of the stem portion of the frame below the hook-like shoulder formation thereon, and each of said fastening elements having an upstanding hook-like formation spaced above said abutment forming end portion which is adapted to be positioned in interlocking engagement with said hook-like shoulder formation on the frame whereby to lock said elements on said frame against rotation in the downward and outward direction relative to said frame.

20. 6. In a mounting for supporting a rim type sink in an apertured supporting structure, a molding frame adapted to be interposed between the sink and an edge of said structure, said molding frame being characterized by a vertically extending flange positioned in the space between the sink rim and the edge of the supporting structure and a laterally extending top portion adapted to overlie the edge of the sink rim and the adjacent edge of said supporting structure, said vertically extending flange having a laterally projecting longitudinally extending shoulder formation adjacent the lower end thereof providing downwardly facing bottom and upwardly and inwardly facing top abutment surfaces, and a plurality of attaching elements for rigidly securing said molding frame to the sink rim, said attaching elements each having an outwardly opening groove in one end edge for receiving said shoulder formation on said flange, said groove providing oppositely disposed upwardly facing and downwardly and inwardly facing abutment surfaces for engagement with the bottom and top abutment surfaces, respectively, on said flange, whereby said attaching elements are connected in interlocked and rigid relation on said frame with the other end of each of said elements extending beneath the sink rim, and said attaching elements each having an adjustable clamping member adjacent the other end for engaging beneath the rim of said sink to rigidly clamp said frame thereto.
